HANDBAG

Arthur Mayer, Maspeth, N. Y.

Application August 14, 1937, Serial No. 159,054

1 Claim. (Cl. 150—28)

My invention relates to handbags and to a method of manufacturing a handbag having a one-piece felted or fabric body.

One of the objects of my invention is to form 5 a handbag by shaping an ordinary unblocked hat body into a handbag body and applying a frame thereto to complete the bag.

Another object of my invention is to manufacture a handbag having a seamless one-piece 10 felted or fabric body and which can be made entirely without stitching.

Another object of my invention is to provide 15 a sturdy handbag which will be most easy to manufacture and which will eliminate most of the steps now practised in the handbag industry, insuring a more economical, stronger handbag and which is moreover of more pleasing appearance than possible by the present method of sewing together the component parts of the bag.

20 Other objects of my invention will appear from the following description, it being understood that the above general statements of the objects of my invention are intended to explain, and not to limit it in any manner.

25 Fig. 1 is a perspective view of an ordinary unblocked hat body as supplied to hat manufacturers.

Fig. 2 is the hat body shown in Fig. 1 in the first stage of blocking to form a handbag body.

30 Fig. 3 is the same hat body after having been further blocked to the desired form.

Fig. 4 illustrates the final step in the formation of the handbag body showing the end walls bent inwardly.

35 Fig. 5 is a top view of the handbag body shown in Fig. 4.

Fig. 6 is a longitudinal section through the completed handbag illustrating the connection of the handbag body to a frame.

40 Fig. 7 is a section along the line 7—7 of Fig. 6.

Fig. 8 is a section on the line 8—8 of Fig. 6.

Referring to the drawing, 1 designates the raw, unblocked hat form which is available in various materials such as felt, soft leathers, fabrics, straw, etc., and which is ordinarily used in the manufacture of hats. These hat forms are well known in the art and are generally produced by attracting hair fibers to a cone-shaped member and thereafter agglomerating these fibers 45 whereby said attracted fibers are matted to-

gether and assume the form of a cup-shaped fabric body.

According to my invention, the hat form is blocked to assume the shape designated as 2 and further blocking produces the body 3. 4 designates the body after the final stage of blocking wherein the end walls are folded inwardly as at 5 and slit at 6, producing two edges 8 on each side of the body.

The skeleton of the handbag is now secured 10 to the body form. The skeleton generally comprises the top frames 9a, the end frames 9, the handle 11, and the inside pocket 12.

The junction of the frames 9 is placed in the crotch at the base of the edges 8. The pivots 15 10 are secured to the frames 9 at their junction, and these pivots 10 support the inside pocket 12 which is thereby suspended in the finished handbag.

The frames 9a and 9 are channel shaped in 20 cross section and the edges 8 are inserted in the channel formed by the frames 9, while the top edges 8a of the body form 4 are inserted in the channel formed by the frames 9a.

The frames are thereafter clamped so as to 25 securely grip the edges 8 and 8a of the body form 4 and this operation completes the handbag. It will be noted that no stitching is required, inasmuch as the original hat body is blocked, slit and the skeleton clamped to its edges.

I have shown a preferred embodiment of my 30 invention and it is obvious that numerous changes and omissions may be made without departing from its spirit.

For example, while I have illustrated my invention as being constructed with a handbag skeleton, a slide fastener, such as a "zipper", may be substituted therefor. In this embodiment, the hookless fastener would be secured to the edges of the handbag body just as a frame and it is 40 understood that my invention covers this variation.

I claim:

In a method of making a handbag from a body 45 of fibers, those steps which comprise blocking said body so as to produce a bag form thereof having a plait at its sides, slitting said plait at the fold, and securing a handbag frame to the top edges of said form and to the side edges formed by said slit.

ARTHUR MAYER.
